UNITARY SOLE AND HEEL FOR FOOTWEAR

Ettore Iorio, 1570 74th St., Brooklyn, N.Y.

Filed Apr. 14, 1961, Ser. No. 64,735

Term of patent 14 years

(Cl. D7—5)

FIG. 2

FIG. 1 is a perspective bottom view of a unitary sole and heel for footwear, showing my new design; and

FIG. 2 is an enlarged sectional view taken on the line D—2 of FIG. 1.

I claim:

The ornamental design for a unitary sole and heel for footwear, substantially as shown.
